UNITED STATES PATENT OFFICE.

JAMES J. SULLIVAN, OF ARAPAHOE COUNTY, COLORADO.

PACKAGE FOR TOILET AND LIKE ARTICLES AND FASTENING MEANS THEREFOR.

Application filed November 18, 1927. Serial No. 234,151.

This invention relates to containers of sanitary and toilet articles and the like and has for an object to provide a handy container or kit for sanitary, toilet and other articles, 5 which container or kit shall be simple and compact, economical as to cost and handy and efficient for use.

A further object is to provide in such a container improved combined fastening and 10 suspending means.

Other objects will appear from the following specification and claims as illustrated in the accompanying drawing in which like reference numerals indicate corresponding parts 15 throughout and in which—

Figure I is a view of the container in perspective with top and bottom partly open and contained articles indicated in dotted lines.

Figure II is a vertical, central, longitudinal 20 section and,

Figure III is a vertical transverse section.

This article is primarily intended for use of automobilists, campers and hikers but is adapted for use under any circumstances 25 where the provision of toilet, sanitary and other articles in compact form for transportation and handy access for use are desired.

The kit or container 1 may be made of any suitable material such as a good grade of card- 30 board or other light reasonably substantial material. A partition shelf 2, dividing the container into upper and lower compartments, is mounted through slots 3 in the ends of the container. The shelf is preferably 35 made of light metal, the lips or flanges 4 being formed by bending the ends of the shelf to a position at right angles with the shelf and in which position the lips or flanges engage the walls of the container and hold the shelf securely in place against movement in 40 any direction.

The container is provided with a cover 5 which may be of the same material as the container and which is preferably simply an extension of one of the walls of the container, the material being bent upon itself at the point of junction between the wall and the cover portion as at 6. When a suitable grade of cardboard or similar material is used, such 50 bend or crease in the material forms a hinge upon which the cover 5 may be opened or closed. Such hinge construction in cardboard articles is common and well understood and needs no further description. The cover is 55 preferably provided with a lip or flange 7 which fits within and against the wall of the

container opposite the hinge-bearing wall. The cover construction is clearly illustrated at Figs. I and III.

A hinged closure 8 for the bottom is pro- 60 vided in a manner substantially the same as the above described construction of the cover 5 and needs no further description, the same being clearly illustrated at Figs. I and III.

The combined fastening and suspending 65 means consists of a cord 9, one end of which is knotted as at 10 below a washer 11 on the under side of the shelf 2. The cord passes through a hole substantially in the center of the shelf 2 and through a corresponding hole 70 12 in the cover 5. When it is desired to secure the container in closed position, the cover 5 and the bottom closure 8 are compressed to the positions indicated in Fig. III and the cord 9 is then wrapped around the box and the 75 end thereof is tied in a simple knot upon itself at a point adjacent the hole 12 in the cover, all as clearly indicated at 13.

When it is desired to suspend the kit for use of the contained articles, the knot is un- 80 tied and the cord 9 is unwound and may be used to hang the kit upon a hook, limb of a tree, or any other suitable object.

The kit is here illustrated as containing 85 toilet articles, as tubes of soap, tooth paste or the like, in the upper compartment and paper towels in the usual folded compact form in the lower compartment. The pack 90 of towels is inserted through the bottom of the kit when the closure 8 is open and slot 14 is provided for withdrawing the paper towels as desired for use. The layers or folds 95 of paper towels as packed within the box are clearly indicated by the dotted lines at the right of Fig. I. The tubes of soap, tooth paste and the like are indicated by the dotted lines in Fig. I above the shelf 2.

When the kit is suspended by the cord 9 the tension upon the cord, resulting from the weight of the loaded kit, will be comparatively small and no difficulty will be experienced in easing such tension sufficiently to permit the cover 5 to open adequately to give free access to the articles contained within the upper compartment above the shelf 2. 100 105

Ordinarily the closure 8 will be constructed with a sufficiently tight fit so that it will remain in closed position even when the weight of the paper towel pack or other article rests upon it but, if desired, any suitable fastening means for this closure may be provided. Such means are not here shown for the rea- 110

son that when properly constructed the tightness of the fit of the closure will be sufficient for the purpose.

It will be noted that the fastening of the cord 9 to the metal shelf 2 in the manner above provided evenly distributes the supporting strain by reason of the stiffness or rigidity of the shelf and the broad bearings of the shelf in the ends of the container. The misshaping of any portion of the device by 10 suspension strain is thereby avoided.

While the contents of the kit or container have been described as toilet or sanitary articles it will be understood that the container may as well be used as a first aid kit and for carrying articles for first aid use as well as 15 a great variety of other articles.

I claim—

1. In a package for toilet and similar articles, a box, a rigid shelf mounted therein and dividing the box into two compartments, 20 closures for each of said compartments and

a combined suspending and fastening member anchored to said shelf and extending through one of said closures.

2. In a package for toilet and similar articles, a box with openings therein, a rigid shelf mounted therein and having broad bearings in the walls of said box, closures for said openings and a member anchored to said shelf and extending outside of said box for alternately fastening said closures and suspending the package.

3. In a package for toilet and similar articles, a box, a rigid shelf mounted therein and dividing the box into two compartments, 30 closures for each of said compartments, a combined suspending and fastening member anchored to said shelf and extending through one of said closures and a slot in one of said compartments for permitting removal of 35 thin articles therethrough.

In testimony whereof, I affix my signature.
JAMES J. SULLIVAN.
